UNITED STATES PATENT OFFICE.

SAMUEL EDWARDS, OF CHARLESTON, WEST VIRGINIA.

RAIL JOINT.

Application filed March 28, 1927. Serial No. 179,127.

This invention relates to rail joints, and more particularly to a combination rail joint and splice plate for use in fastening together the abutted ends of railway rails.

5 It is a general object of this invention to provide a novel and improved form of rail joint.

More particularly, it is an object of this invention to provide a novel and improved 10 rail joint in which the rails are prevented from moving out of alignment with each other in any direction, in which they are prevented from tipping, sliding, or in fact moving in any direction in respect to the tie.

15 Another object of the invention consists in the provision of a splice plate or bed plate and cooperating fish plates or angle bars having interlocking engagement therewith, in order to more securely retain the abutting 20 ends of the rail sections in proper alignment.

A still further object of the invention is to provide a rail joint in which the load on the top of the meeting rail ends will be positively transmitted to the bases of these rail 25 ends by the fish plates or angle bars.

In the accompanying drawings and following specification there is disclosed, by way of example only, a single embodiment illustrative of the present invention with the understanding, however, that various modifications 30 may be made by those skilled in the art in the form, size, proportion and arrangement of the various parts without departing from the spirit of the invention or 35 the scope of the appended claims.

In said drawings:

Fig. 1 is a transverse section through a rail joint constructed according to this invention taken on broken line 1-1 of Figure 2;

Fig. 2 is a side elevation of the joint;

Fig. 3 is a plan view thereof; and

Fig. 4 is a view taken in the same manner as Fig. 1 showing a modified form.

45 The present invention discloses an improved form of splice plate and rail joint particularly adapted to be used with the type of tie disclosed in my prior Patent No. 1,579,860, dated April 6, 1926, but is not limited to use with that particular type of tie. This form of tie, as best shown in Figure 3, comprises a central or main portion 10 of the usual width of a railroad tie but having one end, upon which abutted rails 55 are adapted to be joined, widened by the

addition of the blocks 11 of the same thickness and preferably of the same width as the tie proper. These blocks 11 may be secured to the tie 10 by means of the transverse bolts 12. This widened end of the tie provides 60 additional support where most desired beneath the abutting ends of the pair of rails.

The bed plate or splice plate 13 is arranged transversely of this widened end and is of a length sufficient to cover the three portions 65 of the tie, as shown. The plate is constructed of any suitable material and has a central groove or channel 14 defined by the upwardly and outwardly flaring walls or shoulders 15 which are spaced apart at their 70 bottoms the proper distance to snugly engage the sides of the bases 16 of the abutting rails to thus maintain them in transverse alignment as the bottom 17 of the plate retains them in horizontal alignment. The tips 18 75 of the shoulders are the highest points on the bed plate, from which portions the arcs 19 curve downwardly to the angles 20 below the level of the normal thickness of the bed plate, providing the channels 21 defined on 80 their outer edges by the vertical shoulders or walls 22.

Instead of the usual fish plates which are ordinarily used to join the two sections of rail together, there are provided the special 85 angle bars 23, one on either side of the rail sections. These angle bars are identical and arranged in reversed position, as shown, and each comprises the substantially vertical center portion 24, the bulbous tip 25, the base 90 engaging portion 26, the shoulder 27 and the outer wings ending in the edge 28. This edge 28 is adapted to fit against the shoulder 22, and between this edge and the shoulder 27, the bottom of the angle bar is curved 95 approximately to the form of the arc 19. The shoulder 27 is adapted to abut against the upwardly and outwardly flaring wall 15 which defines the channel in which the rail bases are received. This shoulder 27 is of 100 slightly greater depth than the wall 15, which insures that the weight will be carried by the rail base. The difference in depth of course leaves a tapering air space 34. From this shoulder 27 to the vertical portion 24 the under surface of the angle bar is curved like the upper surface of the rail base, while the vertical portion 24 is of such a height between the rail base and the bulbous portion 25 as to prevent it from con- 110

tacting with the face of the web of the rail.

By referring to Figure 1, it will be seen that the angle bars support the head of the rail from the base of the angle bars, and

5 may be considered as struts extending between 28 and 25, thus preventing any upsetting or rolling over of the rail. The center of curvature of the under surface of the head of the rail is located in such a position that with the rail in place in the bottom of the channel, the angle bars cannot be removed either by rotation around the edge 28 or around the bulbous portion 25, so that they are, in fact, locked in position by the 10 weight of the rail. They are placed in position by first dropping the rail ends into the channel 14 and then setting the angle bars in position with their edges 28 against the shoulders 22 and with the bulbous portions 25 resting against the sides of the rail heads, as shown in dotted lines in Figure 1. The rail sections are then lifted slightly out of the channel to allow the portions 25 to drop beneath the rail heads after which the 15 rails are allowed to return to their position against the bottom of the channel and with the under surface of the head resting on the portions 25 thus locking the angle bars in position.

20 A plurality, preferably four, transverse holes are provided through the vertical portions 24 of the angle bars in register with the usual holes 30 in the webs of the rail ends, to receive the usual bolts 29 for securing the angle bars to the rail sections as is common with the ordinary form of fish plates. In order to fasten the assembled joint to the tie, the holes 31 are provided through the angle bars and the holes 32 25 through the base of the bed plate, these holes being arranged in vertical alignment so that spikes 33 can be driven therethrough to secure the whole assembly to the tie. The holes in the angle bars and the bed plate are spaced just sufficiently apart for the spikes to clear the base of the rail and are spaced longitudinally so as to provide a spike in each section of the tie on either side of the joint, as clearly shown in Figure 3.

30 The structure just described provides a very rigid rail joint, since the channel in the bed plate prevents any horizontal or vertical disalignment of the rails and the bulbous ends of the channeled bars prevent any lateral displacement of the head sections of the rails, assisted in this function not only by the bolts 29, but by the two shoulders of the bed plate against which the angle bars are locked, which locking is increased by 35 weight upon the head of the rail. By having the edges 28 of the angle bars supported at a considerable distance beyond the base of the rail, additional means is provided to prevent any tendency of rolling or upsetting on the part of the rail. The addi-

tional width of tie augments the strengthening effect of the rail joint and supports in an adequate manner the weakest portion of the track.

The bulbous portions 25 of the angle bars, 70 being fully supported from the bed plate, prevent any sagging of the rails at their junction, such as is common with shorter and less effective rail joints of the fish plate type. This joint has been tried and found 75 exceedingly satisfactory on several of the largest railroads in the United States.

The modified form illustrated in Figure 4 shows a joint for a rail having a flat surface under the top portion, and another flat 80 surface on the top of the base portion. The angle bars 23' are therefore provided with flat mating portions, such as 25' and 26'. The portions 24' are also spaced a little farther from the web of the rail, thus increasing the strut effect, to prevent sidewise tipping of the rail. The shoulder 27' does not extend to the bottom of the wall 15', but its depth added to the depth of the rail base, is greater than the height of the wall 90 15', hence a tapering air space 34' is formed, and the weight from the top of the rail is necessarily transmitted to the base portion of the rail. With these differences in construction the joint operates substantially as 95 pointed out in connection with the type shown in Fig. 1.

Having thus described the invention, what is claimed as new and desired to be secured by Letters Patent is:

100

1. A rail joint including in combination, a bed plate provided with a groove to snugly receive the base of a rail, the walls of said groove extending above said base, and there flaring outwardly, a pair of angle bars 105 adapted to be placed one on either side of the rail, said bars being so shaped as to abut beneath the head of said rail and against said flaring walls of said groove and to contact with the top of said rail base 110 whereby the weight of the rail places them under compression.

2. A rail joint including in combination, a bed plate provided with a groove to snugly receive the base of a rail, the walls of 115 said groove extending above said base and flaring outwardly, a shoulder on either side of said groove parallel to the walls thereof, an angle bar for each side of the rail, said bar being so shaped as to engage the 120 wall of the groove and the shoulder and abut beneath the head of the rail to support said head from said bed plate.

3. A rail joint including in combination, a bed plate provided with a groove to snugly receive the base of a rail, the walls of said 125 groove extending above said base and flaring outwardly, a shoulder on either side of said groove parallel to the walls thereof, an angle bar for each side of the rail, said 130

bar being so shaped as to engage the wall of the groove and the shoulder and about beneath the head of the rail to support said head from said bed plate and means to secure said angle bars to said bed plate and to a tie.

4. A rail joint including in combination, a bed plate provided with a groove to snugly receive the base of a rail, the walls of said groove extending above the base, a pair of angle bars adapted to be placed on either side of the rail, said bars being so shaped as to abut beneath the head of said rail and also against the rail base, and each having a shoulder adapted to abut against the walls of said groove, said shoulders being of a depth to leave an air space above said walls whereby the weight of said rail is constrained to be transmitted to said rail base by said angle bars.

5. A rail joint including in combination, a bed plate provided with a groove to snugly receive the base of a rail, the walls of said

groove extending above the base, a pair of angle bars adapted to be placed one on either side of the rail, said bars being so shaped as to abut beneath the head of said rail and having shoulders adapted to abut against the walls of said groove, said shoulders being of greater depth than said groove, whereby the weight of the rail is transmitted to said rail base.

6. A rail joint including in combination, a bed plate provided with a groove to snugly receive the base of a rail, a pair of angle bars adapted to be placed one on either side of said rail, and means on said bars for supporting said rail from said bed plate to take side thrust, and other means to prevent said means from taking vertical thrust, said other means providing an air space above the portion of the bed plate outside of the rail groove.

In testimony whereof I hereunto affix my signature.

SAMUEL EDWARDS.
